NATIONAL MANUFACTURING COMPANY, OF STERLING, ILLINOIS, A CORPORATION
OF ILLINOIS

DOOR HANGER

Application filed May 7, 1928. Serial No. 275,592.

Our invention relates to hangers for doors and has for one of its objects the provision of an improved hinged hanger which permits the door to swing in one direction about its 5 suspension-support to prevent breakage of the door or hanger, or both, in case force is applied to the door as by an object striking the same in its movement through the doorway.

10 Another object is to provide a hinging hanger which includes a trolley structure for freely sliding the door along a suspension trackway, and which also includes a pivotal connector between the trolley and door which 15 permits ready movement of the trolley along a straight, curved or other irregularly shaped trackway.

A further object is to provide a hanger of the foregoing character in which the hinging 20 relation does not in any way impair the strength and durability of the hanger as a whole and which is adapted to provide a solid connection between the door and trolley in the normal vertical or suspended position of 25 the door so as to resist force applied in a direction opposite that in which it hinges.

Additional objects are to increase the efficiency of the hanger as a whole; to provide structural simplicity and ease in installation; 30 and to provide cheapness of construction with economy in manufacture.

Other objects and advantages will become apparent as this description progresses and by reference to the drawing wherein,

35 Figure 1 is a front elevation of a hanger embodying my invention and shown applied to a so-called sliding door;

Fig. 2 is a side elevation, partially in section, of the structure of Fig. 1, showing the 40 hanger in full lines in its normal door-vertical or door-suspending position, and in dotted lines in a hinging position with the door swing outwardly as a result of force being applied thereto; and

45 Fig. 3 is a horizontal section taken substantially on line 3—3 of Fig. 1.

We will describe our invention as applied to a door 10 which is of a size adapted to cover one-half or the entire doorway, but it 50 is to be understood that it may be equally

well applied to, and will serve its intended purpose equally as well when applied to a door of a type comprising a plurality of sections hinged together and movably supported from the top by hangers embodying our 55 invention and which are applied to one or more of such sections.

A trackway 11 which receives and guidingly supports the door trolley 12 is mounted along the doorway in such a manner that door 10 may be moved back and forth therealong as will become obvious as this description continues. The trolley is comprised of four wheels 12^a rotatably mounted upon a carriage part 12^b which pivotally receives the headed 60 connector pin or bolt 13 which supports the door 10 and permits relative turning movement between the trolley and door.

An L-shaped bracket 14 is secured to the 65 top part of the door by bolts 15 and nuts 15^a with its horizontal leg 14^a seated upon the top edge of the door. This horizontal leg is provided with two upwardly extending and spaced ears 16, 16', preferably, but not necessarily, struck therefrom so as to be 70 integral therewith. These ears are slightly off-center being so located as to be slightly to the rear of the central vertical plane of the door 10 and bracket 14.

The door bracket 14 is hingedly connected 75 to the pin 13 by an inverted U-shaped hinge member 17, the legs 17^a of which are hingedly mounted upon the bracket ears 16 by hinge pins 18, 18', which pass through 80 aligned opening in such legs and ears. The upper or horizontal top part 17^b of this member is provided with a slot 19 (Fig. 3) which is adapted to adjustably receive the free and threaded end of the connector pin 13. This pin is secured to the member 17 by nuts 20 and 21 located above and below 85 the U-base 17^b thereof, respectively, the nut 21 serving as an adjusting nut while the other nut serves to lock the parts in their 90 adjusted position in a manner which will be well understood. The pin 13 is provided with opposed flat sides 13^a adapted to receive a wrench to permit of vertical adjustment of the door without detachment of parts 95

upon loosening the nut 20 and revolving the pin 13.

The U-hinge member 17 is so shaped that the door may hinge in one direction relative to its support, but not in the opposite direction. More specifically, the front edges of this member are cut away to a like extent from near the upper part, tapering rearwardly toward the hinge as indicated at 17^a. The bottom edges of each U-leg is also cut away slightly toward the rear as at 17^a or the bottom edges may be extended slightly at the rear, to provide leg projections 22 which are adapted to seat upon the rear top part of the bracket 14 when the door is in its normal suspended or vertical position.

The hinge pins 18, 18' are so located that the hinge is slightly to the rear of the central plane of the door and the axis of the connector pin 13, and this relation between the hinge and the parts mentioned is accomplished, in part, and maintained by adjusting the end of the connector pin 13 forwardly in the slot 19 in the top 17^a of the hinge member. The same size bracket 14 may be used with doors of different thickness, thereby changing the hinge relation shown in Fig. 2 to some extent. The lateral adjustment slot 19 enables adjustment of the hinge member 17 and, in turn, the hinge to provide and maintain the desirable off-center relation of the hinge upon such variation in door thickness.

From the foregoing, it will be obvious that when force is applied to the side A of the door 10, as by the impact of some object such as part of a vehicle in its movement to or from a garage, the door will yield or move about the hanger hinge to or toward the dotted line position of Fig. 2. When this force is removed, the door will swing back to the full-line position of Fig. 2, the movement of the door about the hinge in this latter direction being stopped by the projecting legs 22 of the U-shaped hinge member 17 engaging the top 14^a of the L-shaped door bracket. In the normal suspended or vertical position of the door (Fig. 2) the connection between the door and the connecting pin 13 is a rigid one in the same manner as if the bracket 14 and pin 13 were a solid part without any intervening hinge. This relation is maintained, except when a sufficient counter force is applied to side A of the door, by locating the hinge rearwardly of the vertical center plane of the door 10 which permits the weight of the door to at all times tend to swing it rearwardly and hold the leg projections 22 and bracket top 14^a in solid engagement.

Our hanger may be applied to a door mounted to move either along the outside or along the inside wall of the building which may be a garage, barn, etc. The side

A of the door, whether it is mounted inside or outside the building, will be next to the adjacent wall surface of the building in its open position and this will support the door in case of impacts applied to side B thereof. The size and weight of the doors may vary and the size and number of hangers employed may be varied accordingly. Furthermore, it is to be understood that while we have shown only one form of our invention, changes in details and arrangement of parts may be made without departing from the spirit and scope of our invention as defined by the claims which follow.

We claim:

1. The combination with a door and a supporting trackway, of a door hanger including a wheeled-carriage adapted to move along upon said trackway, a depending connector pivotally carried by said carriage, a bracket secured to said door, a member carried by said depending connector, and a hinge connection between said bracket and member, said member limiting the movement of said hinge to one direction only from normal position by applying a force thereagainst in a substantially vertical direction.

2. The combination with a door and a supporting trackway, of a door hanger which comprises a wheeled-trolley carriage, a depending member pivotally carried by said carriage, an inverted L-shaped bracket secured to said door with its horizontal flange extending across the top edge of the door, upstanding spaced hinge members carried by the horizontal flange of said bracket, an inverted U-shaped hinge element carried by said depending member, means for hingedly connecting the legs of said U-shaped element and said hinge members together at a point rearwardly of the vertical axis of said connecting member and the vertical central plane of said wheeled carriage so that the weight of said door will always tend to swing said door rearwardly when unrestrained, and said U-element legs being shaped to oppose said rearward door movement by exerting a downwardly applied force to the upper edge of said door.

3. In a door hanger adapted to be suspended from a trackway, a wheeled-carriage adapted to move along said trackway, a connecting member centrally and pivotally carried by said carriage, a bracket adapted to be carried by and extend above and over the top edge of the door, hinge elements carried by said bracket at a point above the door and rearwardly of the central vertical plane thereof, a hinge member adjustably carried by said connecting member and having hinge elements located rearwardly of the point of connection between said two members, said latter hinge elements being uni-directional, and means for connecting said first and second named hinge elements together to form

5 a uni-directional off-center hinge between said carriage and bracket, the contacting force between said latter hinge elements and the door being exerted in a direction substantially lengthwise of the door.

10 4. In a hanger bracket, a supporting member, a depending connector member centrally and pivotally carried by said supporting member, a door bracket having a horizontal flange, spaced hinge elements carried by said bracket flange, an inverted U-shaped hinge member having depending legs with rearwardly tapering forward edges and straight rear edges extended to form downwardly extending stop-legs, means for adjustably securing said connector member to the forward part of said hinge member, and means for hingedly securing said hinge member, at the rear thereof, to said hinge elements, whereby the hinge between said connector and bracket is to the rear of the vertical center of said connector and carriage and permits forward hinging movement of said door bracket and said leg-stops prevent rearward hinging movement of said bracket and effect a solid connection between said bracket and connector member in the normal suspended position of the door.

15 5. In a door hanger, a supporting member, a connector element carried centrally by said supporting member, a door bracket, and a uni-directional hinge between said bracket and connector element comprising spaced hinge elements carried by said bracket, an inverted U-shaped hinge member having a slot in its horizontal web part, the depending flanges of said hinge member having their forward edges tapered downwardly and inwardly and their rear edges straight and downwardly extended to form extended legs, means for hingedly connecting said depending flanges near the rear edges thereof to said hinge elements, the tapered edges of said flanges permitting forward hinging of said bracket and said legs prevent hinging of said bracket rearwardly from its normal vertical position, and means for adjustably securing said connector element in said hinge member slot at the forward part thereof so that said hinge is located rearwardly of the central vertical plane of said connector element and supporting member and so that the weight of the door adapted to be attached to said bracket will always swing the door rearwardly about said hinge, when unrestrained, to a normal vertical position where said hinge member legs seat solidly upon said bracket.

20 6. In a door hanger, a support, a connector member dependently carried by said support, a bracket adapted to be secured to the door, another bracket carried by said connector member, and a hinge between said two brackets and offset rearwardly of the central vertical plane of said support and

25 connector member, said last-named bracket being formed to engage said first bracket in a substantially vertical direction to render said hinge uni-directional.

30 7. In a door hanger, a support, a connector member dependently carried by said support, a bracket adapted to be secured to the door, another bracket vertically and laterally adjustable, means for connecting said latter bracket and said connector member, and a hinge between said two brackets and offset rearwardly of the central vertical plane of said support and connector member, said last-named bracket being provided with downwardly extending stop elements limiting the hinging movement of the door in one direction only from its normally suspended or vertical position.

35 8. The combination with a door and a supporting trackway, of a door hanger including a wheeled carriage adapted to move along upon said trackway, a connector carried by said carriage and having a depending threaded end, a bracket secured to said door, a member carried by said depending connector, means associated with the threaded end of said connector and said member for adjusting said member vertically and laterally, and a hinge connection between said bracket and member, said member being formed to engage said door and to apply a substantially vertical force against the upper edge thereof.

40 9. In a hanger bracket, a supporting member, a depending connector member centrally and pivotally carried by said supporting member, a door bracket having a horizontal flange, spaced hinge elements carried by said bracket flange, an inverted U-shaped hinge member having depending legs with rearwardly tapering forward edges, straight rear edges extended to form downwardly projecting stop-legs, means for securing said connector member to said hinge member, and means for hingedly securing said hinge member, to said hinge elements, said last named means being located rearwardly of the vertical axis of said carriage and said connector and also rearwardly of a vertical line passing through the center of gravity of said door, whereby inward movement of said door is limited by engagement of said stop-legs therewith.

45 In testimony whereof, we have subscribed our names.
